CONTROL APPARATUS FOR RAILWAY
SIGNALING MEANSWesley B. Wells, Wilkinsburg, Pa., assignor to
The Union Switch & Signal Company Swiss-
vale, Pa., a corporation of Pennsylvania

Application May 29, 1943, Serial No. 489,009

13 Claims.

(Cl. 246—223)

My invention relates to control apparatus for railway signaling means, and more particularly to control apparatus wherewith two electromagnets having tractive type armatures which jointly govern a signaling member are selectively energized through a polarized supply circuit.

An object of my invention is the provision of novel and improved control apparatus wherewith a member is selectively governed to different positions by two electromagnets.

Another object of my invention is the provision of improved control apparatus wherewith two electromagnets having interconnected tractive type armatures for joint operation of a member are energized by a polarized line circuit and the armature of one of the magnets is locked or otherwise retained at its released position when current of a given polarity is supplied to that magnet, and the other magnet is energized at the same polarity regardless of the polarity of the current of the supply circuit.

Still another object of my invention is the provision of improved control apparatus of the type here involved and wherewith one of two electromagnets having tractive type armatures is equipped with contacts through which the connection of the other magnet is controlled to govern the polarity of the energization of such other magnet.

Other objects, features and advantages of my invention will appear as the specification progresses.

According to my invention, a supply circuit including a source of direct current and a pole changer supplies current of different polarities to the windings of a pair of electromagnets, the windings of the electromagnets being either connected in series or in multiple to the circuit. These magnets are provided with tractive type or neutral armatures which preferably are interconnected for joint operation of a signal actuating member to different positions according to the released and picked-up positions of the armatures. One of the electromagnets is equipped with locking or retaining means to retain the neutral armature of such one magnet at its released position when the current is of a preselected polarity, but such locking means is ineffective and the neutral armature is free to pick up when the current is of the opposite polarity. This one electromagnet is equipped with contacts which are actuated when the magnet is conditioned to pick up its neutral armature, and these contacts are used either alone or with asymmetric units to govern the connection to the

winding of the other one of the electromagnets in such a manner that the current flows always in the same direction in the winding of the other magnet irrespective of the polarity of the current of the supply circuit.

5 The second mentioned electromagnet is provided with a retaining characteristic, such as a slow release period and its armature is retained picked up during pole changing periods of the supply circuit. The two neutral armatures of this pair of electromagnets are thus operated to different positions according to the polarity of the current of the supply circuit, and being interconnected they are effective to move a signal actuating member to any one of three positions, a first position when the electromagnets are deenergized and both neutral armatures are released, a second position when current of a preselected polarity is supplied and the armature of the first 10 mentioned electromagnet is retained at the released position but the armature of the second mentioned electromagnet is picked up, and to a third position when current of the polarity opposite the preselected polarity is supplied and the armatures of both magnets are picked up.

I shall describe several forms of apparatus embodying my invention, and shall then point out the novel features thereof in claims.

15 In the accompanying drawings, Figs. 1, 2, 3, 4 and 5 are diagrammatic views showing five different forms of the apparatus, each of which form of apparatus embodies my invention when used for searchlight type of railway signals.

20 In each of the several views like reference characters are used to designate similar parts.

25 It is to be understood that my invention is not limited to searchlight type of railway signals, and this one application serves to illustrate the many places where apparatus embodying my invention is useful.

30 Referring to Fig. 1, the reference characters L₁ and L₂ designate the two conductors of a line or supply circuit which includes a pole changer PC and a source of direct current, such as a battery B₁, the positive and negative terminals of the battery being indicated by plus and minus signs respectively. Pole changer PC may be manually operated or may be operated automatically 35 in accordance with different traffic or other conditions. At a mid position, that is, the position of pole changer PC shown in the drawings, the supply circuit is without current, at a lower position of the pole changer, current which I shall 40 call normal polarity is supplied to the circuit,

and at an upper position of the pole changer the current is of reverse polarity.

The reference characters **M1** and **M2** designate a first and a second electromagnet, respectively. These electromagnets are preferably similar in construction and may take any one of several well-known arrangements. As shown, each magnet **M1** and **M2** has a magnetizable core **MC** which terminates in two pole pieces **1** and **2**, and with which pole pieces a tractive type armature cooperates, an armature **A1** being pivoted at **3** for swinging movement toward and away from pole pieces **1** and **2** of magnet **M1**, and an armature **A2** being pivoted at **4** for swinging movement toward and away from pole pieces **1** and **2** of magnet **M2**. In Fig. 1, magnet **M1** is further provided with a polar armature **P1**, comprising a permanent magnet **5** having a north pole **N** and a south pole **S** and pivoted at **6** for swinging movement either to the left toward pole piece **1** or to the right toward pole piece **2** according to the polarity of the pole pieces **1** and **2** as created by the energization of magnet **M1**. Furthermore, polar armature **P1** is disposed so that when it swings to the left toward pole piece **1** in response to energization of magnet **M1** of a pre-selected polarity, the free end of armature **P1** swings to a position where it is adjacent a non-magnetizable strip **7** carried on armature **A1** and the polar armature **P1** mechanically locks the neutral armature **A1** against movement toward the pole pieces. When magnet **M1** is energized at a polarity such that polar armature **P1** swings toward pole piece **2**, the free end of armature **P1** swings away from the strip **7** and the neutral armature **A1** is free to move toward the pole pieces in response to the attraction created by energization of the magnet. Also, polar armature **P1** is disposed to remain in the position to which it was last moved when the magnet **M1** is deenergized, and is characterized by movement to the opposite position when current has been applied to the magnet for an interval sufficient to move the armature away from its last position, even though such energization is interrupted during the movement of the armature. In other words, when magnet **M1** is deenergized, its neutral armature **A1** falls by gravity to a released position, when the magnet **M1** is energized by current of a preselected polarity polar armature **P1** swings to the left toward pole piece **1** and mechanically locks the neutral armature **A1** at the released position, but when magnet **M1** is energized by current of a polarity opposite this preselected polarity, the polar armature **P1** swings to the right toward pole piece **2** and the neutral armature is unlocked and attracted to a picked-up position.

Polar armature **P1** of magnet **M1** is operatively connected to a contact member **8** as indicated by a dotted line **9**, and contact member **8** is moved to engage either a normal contact **10** or a reverse contact **11** according to the position of the polar armature.

Magnet **M1** is provided with two windings **12** and **13** which are mounted on the core **MC** in such a manner as to create additive fluxes when these windings are energized in series. Similarly, magnet **M2** is provided with two windings **14** and **15** which are mounted on its magnetic core in such a manner as to create fluxes that add when the windings are energized in series.

The neutral armatures **A1** and **A2** are preferably interconnected by any suitable linkage, and in Fig. 1 a floating lever **16** has its ends connect-

ed to the free ends of armatures **A1** and **A2** by means of a pin and slot connection **17**. One end of a link **18** is pivotally connected to the floating lever **16** intermediate its ends, and the other end of link **18** is pivotally connected to a lug **19** formed on one side of a signal actuating member **20**, member **20** being pivotally supported at **21**. This actuating member **20** is disclosed as a spectacle arm of a searchlight type of railway signal and is provided with three color filters or roundels **R**, **Y** and **G**, arranged to cooperate with an electric lamp **SL**. In the drawings, the lamp **SL** is shown above the filters for the purpose of illustration, and it is to be understood that in actual practice this lamp is located for the filters to be moved consecutively in front of the lamp when the member **20** is rotated about its pivot **21**. The arrangement of this linkage is such that when both armatures **A1** and **A2** are released the member **20** is biased by the armatures to a first position where the filter **R** is positioned before the lamp **SL** to provide a red signal light, when either armature **A1** or **A2** is attracted to its picked-up position and the other armature is released, the member **20** is moved to a second position where the filter **Y** is positioned before the lamp to provide a yellow signal light, and when both armatures **A1** and **A2** are picked up the member **20** is moved to a third position where filter **G** is positioned before the lamp to provide a green signal light.

The electromagnets **M1** and **M2** are energized by the polarized supply circuit referred to hereinbefore, and it is believed that the connection of the windings of the magnets to conductors **L1** and **L2** of the supply circuit can best be understood by a description of the operation of the apparatus.

In describing the operation of the apparatus of Fig. 1, I shall first assume that pole changer **PC** occupies its mid position and no current is supplied to the line circuit with the result that both magnets **M1** and **M2** are deenergized and both armatures **A1** and **A2** are released so that member **20** is operated to its first position where the filter **R** is before the lamp **SL**.

I shall next assume that the pole changer **PC** is moved to its lower position and at which position current flows from the positive terminal of battery **B1** through contact member **22** of pole changer **PC**, conductor **L1**, winding **13** of magnet **M1**, normal polar contact **8—10** of magnet **M1**, wire **23**, windings **14** and **15** in series of magnet **M2**, an asymmetric unit **24** in its forward direction, wire **25**, winding **12** of magnet **M1**, conductor **L2** and contact member **26** of the pole changer to the negative terminal of battery **B1**. To agree with the assumption made hereinbefore, the current supplied to the line circuit is of normal polarity and the parts are preselected for current of normal polarity to energize magnet **M1** as required to operate its polar armature **P1** to the left to mechanically lock the neutral armature **A1** in the released position and to close normal polar contact **8—10**. Armature **A2** of magnet **M2** is, however, attracted to its picked-up position due to the energization of windings **14** and **15**, with the result that the signal actuating member **20** is moved to its second position where the filter **Y** is positioned before the lamp **SL**.

I shall next assume that the pole changer **PC** is operated from its lower to its upper position. Current now flows from the positive terminal of battery **B1** through contact member **22** of the

pole changer, conductor **L2**, winding **12**, wire **25**, an asymmetric unit **27** in its forward direction, wire **23**, polar contact **8—10**, winding **13**, conductor **L1** and contact member **26** to the negative terminal of the battery. The electromagnet **M1** only receives current at this time and its energization is opposite to that of the previous case with the result the polar armature **P1** is moved to the right where it unlocks the neutral armature **A1** and closes the reverse polar contact **8—11**. The opening of normal polar contact **8—10** and the closing of reverse polar contact **8—11** causes current to flow from battery **B1** the same as traced above up to wire **23**, thence through windings **14** and **15** of magnet **M2**, wire **28**, reverse polar contact **8—11**, winding **13**, conductor **L1** and contact member **26** to the negative terminal of the battery. Magnets **M1** and **M2** are now energized in series, the energization of magnet **M1** being of reverse polarity so that polar armature **P1** is held at the right and neutral armature **A1** is picked up. The current flows in windings **14** and **15** of magnet **M2** in the same direction as in the previous case, and its armature **A2** is retained picked up. It should be pointed out that asymmetric units **24** and **27** in series form a low resistance path across windings **14** and **15** and provide the electromagnet **M2** with a slow release characteristic, the slow release period being sufficiently long to bridge the usual pole changing period of pole changer **PC** plus the period required for operation of polar armature **P1** of the magnet **M1**, and consequently the armature **A2** of magnet **M2** is held picked up during the reversal of the polarity of the current supplied to the conductors **L1** and **L2**. Such retaining of armature **A2** in its picked-up position during pole changing period of the supply circuit is essential in control of railway signaling means, such as searchlight signals, in order to avoid a momentary flash of the red signal light. With both armatures **A1** and **A2** picked up, the member **20** is operated to its third position to bring the filter **G** before the lamp **SL**.

In the event pole changer **PC** is operated back from its upper position to its lower position, current first flows from positive terminal of battery **B1** through contact member **22**, conductor **L1**, winding **13**, reverse polar contact **8—11**, wire **28**, asymmetric unit **24**, wire **25**, winding **12**, conductor **L2** and contact member **26** to the negative terminal of the battery, and magnet **M1** alone is energized at normal polarity. Such reversal of the energization of magnet **M1** causes the magnetic flux to die down, pass through zero and build up in the opposite direction, the neutral armature **A1** being released during the time the flux passes through zero so that when the energization builds up in the normal direction the polar armature **P1** is operated to the left where it mechanically locks the neutral armature **A1** at the released position. After such operation of magnet **M1**, the closing of normal polar contact **8—10** connects the windings of the two magnets in series to the supply circuit as previously traced, and since the current continues to flow in the same direction in the windings **14** and **15** of magnet **M2**, its armature **A2** is retained picked up. Thus armature **A1** is now released and armature **A2** is retained picked up and member **20** is moved back from its third position to its second position.

It follows from the foregoing description that in Fig. 1 the windings of the two magnets are

energized in series, the energization of magnet **M1** being of normal polarity or reverse polarity according to the normal or reverse polarity of the current of the supply circuit, and contact member **8** of magnet **M1** together with asymmetric units **24** and **27** serve to cause the current to flow always in the same direction through the windings of magnet **M2**. Also magnet **M2** retains its neutral armature picked up during a pole changing period of the supply circuit due to the slow release characteristics of this magnet as effected by the asymmetric units **24** and **27**.

In Fig. 2, the apparatus is similar to that of Fig. 1 except the single contact member **8** actuated by polar armature **P1** is replaced by pole changing contact members **29** and **30**, asymmetric units **24** and **27** are omitted and another asymmetric unit **31** is interposed in the connection between windings **14** and **15** of magnet **M2**, and the magnet **M2** is provided with a short circuited winding **36**.

It is believed that the apparatus of Fig. 2 can best be understood by a description of its operation, and assuming that the pole changer **PC** is at the mid position to disconnect battery **B1**, the magnets **M1** and **M2** are deenergized with the result both armatures **A1** and **A2** are released and member **20** is actuated to its first position. With pole changer **PC** of Fig. 2 moved to its lower position, current flows through conductor **L1**, windings **13** and **12** of magnet **M1** and conductor **L2** back to battery, and magnet **M1** is energized at normal polarity as required to operate its polar armature **P1** to the left where it locks the neutral armature **A1** at the released position and operates contact members **29** and **30** to the left to close normal polar contacts **32** and **33**. Subsequent to such operation of magnet **M1**, current flows from battery **B1** through conductor **L1**, polar contact **29—32**, winding **14** of magnet **M2**, asymmetric unit **31** in its forward direction, winding **15** of magnet **M2**, polar contact **30—33** and conductor **L2** back to battery **B1**, and magnet **M2** is energized to pick up its neutral armature **A2** so that the signal actuating member **20** is moved to its second position.

Operation of pole changer **PC** of Fig. 2 to its upper position reverses the current supplied to windings **12** and **13** of magnet **M1** and magnet **M1** is energized to operate its polar armature **P1** to the right where it unlocks armature **A1** and moves contact members **29** and **30** to engage reverse polar contacts **34** and **35**, respectively. Armature **A1** of magnet **M1** is now free to pick up. The closing of the reverse polar contacts of magnet **M1** permits current to flow from battery **B1** through conductor **L2**, reverse polar contact **30—35**, winding **14**, asymmetric unit **31**, winding **15**, reverse polar contact **29—34**, and conductor **L1** through the pole changer to battery **B1**. This reversing of the connections to the windings **14** and **15** of magnet **M2** by the contacts of magnet **M1** causes current to flow in the windings of magnet **M2** in the same direction, although the polarity of the current of the supply circuit has been reversed, and hence magnet **M2** retains its neutral armature **A2** in the picked-up position, magnet **M2** being provided with a slow release characteristic due to the short circuited winding **36**. With both armatures **A1** and **A2** of Fig. 2 picked up, the associated signal actuating member **20** is moved to its third position.

It is to be observed that the asymmetric unit **31** blocks the flow of current through windings **14** and **15** in the opposite direction during the

brief interval the normal polar contacts 32 and 33 of magnet M1 remain closed subsequent to movement of the pole changer PC to its upper position.

Operation of the pole changer PC of Fig. 2 back to the lower position, causes the energization of magnet M1 to be of normal polarity, with the result that the neutral armature A1 is released as the flux of magnet M1 passes through zero and then is locked in the released position because polar armature P1 is operated to the left as a result of such normal energization of the magnet. Also, the normal polar contacts 32 and 33 of magnet M1 are now closed and current flows in windings 14 and 15 of magnet M2 in the same direction as before, and its armature A1 is held picked up so that member 20 is moved back to the second position.

It follows that in Fig. 2, the magnets M1 and M2 are energized from the supply circuit in multiple, magnet M1 is energized at normal or reverse polarity according to the polarity of the current of the supply circuit, and pole changing contact members 29 and 30 of magnet M1 serve to reverse the connection to the windings of magnet M2 so that magnet M2 is always energized at the same polarity. Also armature A1 is mechanically locked at its released position when the magnet M1 is energized at normal polarity, and the magnet M2 retains its neutral armature picked up during the pole changing period of the supply circuit due to the slow release period effected by the short circuited winding 36.

In Fig. 3, the apparatus is the same as in Fig. 1 except magnet M1 is varied in its construction in that polar armature P1 and contact member 8 are removed, a hold down permanent magnet 37 is added and a contact member 38 is attached to the neutral armature A1.

Permanent magnet 37 is L-shaped having one end secured to the pole piece 2 of magnet M1 and its other end extending underneath the free end of neutral armature A1. Thus armature A1 in its released position is in close proximity to one pole of the permanent magnet 37. Assuming the lower end of permanent magnet 37 to be a north pole and its upper end to be a south pole, as indicated by the letters N and S in the drawings, and the windings 12 and 13 of magnet M1 are deenergized, the armature A1 drops under the influence of gravity to the released position, and under such conditions the permanent magnet 37 exerts a pull on armature A1 to assist in holding the armature at the released position. When windings 12 and 13 are energized by current that causes the pole piece 2 to become a south pole and pole piece 1 to become a north pole, the magnetic flux from permanent magnet 37 and the flux from the electromagnet oppose each other and a point is reached at which the pull or attraction exerted on armature A1 by the electromagnet exceeds the downward pull of the permanent magnet plus the force of gravity, and the armature A1 is picked up. If when armature A1 occupies its released position, the windings 12 and 13 are energized by current of a polarity that causes pole piece 2 to be a north pole and pole piece 1 to be a south pole, the flux of the electromagnet aids the flux of the permanent magnet and the armature A1 is held at the released position.

In Fig. 3, the magnets M1 and M2 are connected to the supply circuit in series in a manner similar to that in Fig. 1. When pole changer PC of Fig. 3 occupies its mid position and both mag-

nets are deenergized, the member 20 is biased by gravity to its first position. When the pole changer occupies the left-hand position and current of normal polarity flows from the positive terminal of battery B1 through contact member 22, conductor L1, winding 13, transfer contact 39 and back contact 40 of a continuity type of contact, windings 14 and 15 of magnet M2, asymmetric unit 24, wire 25, winding 12 of magnet M1, conductor L2 and pole changer contact member 26 to the negative terminal of battery B1, the magnet M1 is energized in a manner that its neutral armature A1 is held at the released position, but the neutral armature A2 of magnet M2 is picked up, with the result that member 20 is operated to its second position in response to current of normal polarity of the supply circuit.

When pole changer PC of Fig. 3 is moved to the right-hand position, current flows from the positive terminal of battery B1 through conductor L2, winding 12, wire 25, asymmetric unit 27, back contact 39-40 of magnet M1, winding 13 and conductor L1 to the other terminal of battery B1. The energization of magnet M1 is now such that its armature A1 is free to pick up and windings 12 and 13 are directly across the line circuit and therefore over-energized which overcomes a stronger permanent magnet 37 than could otherwise be used. The opening of back contact 39-40 and the closing of front contact 33-39 of magnet M1 connects windings 14 and 15 of the magnet M2 in series with the windings of magnet M1 to the supply circuit, current flowing through windings 14 and 15 in the same direction as in the previous case. Since magnet M2 is slow to release due to asymmetric units 24 and 27, its armature A2 is retained picked up during this pole changing period of the supply circuit, and with both armatures A1 and A2 picked up in response to current of reverse polarity supplied to the supply circuit, the member 20 is operated to its third position.

It follows that in Fig. 3 magnet M1 is energized either at normal or reverse polarity according to the polarity of the current of the supply circuit, and is deenergized when the supply circuit is without current and its neutral armature A1 is retained at the released position during the time the magnet M1 is energized at normal polarity due to the function of permanent magnet 37. Also the contact members of magnet M1, together with the asymmetric units 24 and 27, cause the current to flow in the windings of the magnet M2 always in the same direction irrespective of the polarity of the current of the supply circuit.

In Fig. 4, the apparatus is the same as in Fig. 3 except magnet M1 is provided with pole changing contact members 41 and 42 operated by its neutral armature A1, magnet M2 is provided with a short circuited winding 36 to effect a predetermined slow release period, and the windings M1 and M2 are connected to the supply circuit in multiple, the same as in Fig. 2.

With pole changer PC of Fig. 4 set at the mid position the supply circuit is without current and member 20 is operated to its first position due to the force of gravity on the neutral armatures of the magnets.

With pole changer PC of Fig. 4 set at the left-hand position, so that current of normal polarity is supplied to conductors L1 and L2 of the supply circuit, the magnet M1 whose windings 12 and 13 are connected across the conductors L1 and L2,

is energized at normal polarity and its neutral armature A_1 is held at the released position due to the action of permanent magnet 37 . Current also flows through conductor L_1 , wire 43 , back contact $42-44$ of magnet M_1 , wire 45 , winding 14 , asymmetric unit 31 , winding 15 of magnet M_2 , wire 46 , back contact $41-47$, wire 48 and conductor L_2 back to the battery. Thus magnet M_2 is energized and its neutral armature A_2 is picked up to operate member 20 to the second position. Operation of pole changer PC of Fig. 4 to its right-hand position, causes the current supplied to the conductors L_1 and L_2 and in turn to the windings 12 and 13 of magnet M_1 to be of reverse polarity with the result that magnet M_1 is energized at reverse polarity and its neutral armature A_1 is picked up. The picking up of armature A_1 operates pole changing contact members 41 and 42 to pole change the connection of windings 14 and 15 of magnet M_2 to the conductors L_1 and L_2 of the supply circuit, and consequently current flows in the windings 14 and 15 in the same direction as before, and the armature A_2 of magnet M_2 is retained picked up, armature A_2 being held in the picked-up position during the pole changing period of the supply circuit due to the slow release period of magnet M_2 as effected by the short circuit winding 36 . It is to be noted that asymmetric unit 31 blocks the flow of current through windings 14 and 15 in the opposite direction during the brief period back contacts 44 and 47 of magnet M_1 remain closed subsequent to movement of pole changer PC. With both neutral armatures A_2 and A_1 in the picked-up position, the member 20 is moved to the third position. Operation of the apparatus of Fig. 4 in response to a movement of pole changer PC back to its left-hand position from the right-hand position is substantially the same as described for the apparatus of Fig. 2, and the description need not be repeated.

It follows that in Fig. 4, the magnet M_1 is energized at either normal or reverse polarity according to the position of the pole changer of the supply circuit and armature A_1 is retained at the released position when the magnet M_1 is energized at normal polarity but is picked up when it is energized at reverse polarity. Also pole changing contact members 41 and 42 of magnet M_1 serve to reverse the connection of the windings of magnet M_2 to the supply circuit so that magnet M_2 is always energized at the same given polarity regardless of the polarity of the current of the supply circuit.

In Fig. 5, the apparatus is similar to that of Fig. 3, except magnet M_1 is modified by the permanent magnet 37 being removed and a differential winding 49 being added. Winding 49 is made of substantially the same number of turns as windings 12 and 13 taken together.

With pole changer PC of Fig. 5 set at the mid position, both magnets are deenergized and member 20 is biased to its first position the same as in the previous forms of the apparatus. With pole changer PC of Fig. 5 set at the left-hand position, current is supplied through conductor L_1 , winding 13 , back contact $39-40$, winding 14 of magnet M_2 , winding 49 of magnet M_1 , winding 15 of magnet M_2 , asymmetric unit 24 , wire 25 , winding 12 of magnet M_1 , conductor L_2 and back to battery B_1 . Current thus flows in the several windings in series. Differential winding 49 is disposed to create a flux that opposes the flux created by windings 12 and 13 with the result that the resultant flux of magnet M_1 is substantially

zero and its neutral armature A_1 is retained at the released position. Magnet M_2 , however, is energized to pick up its neutral armature A_2 , and member 20 is moved to the second position.

Assuming pole changer PC of Fig. 5 is moved to the right-hand position to reverse the polarity of the current supplied to conductors L_1 and L_2 , current flows through conductor L_2 to winding 12 , wire 25 , asymmetric unit 27 , back contact $39-40$, winding 13 and through conductor L_1 to the supply source. Windings 12 and 13 of magnet M_1 are now energized, but winding 49 is without current and consequently magnet M_1 is energized to pick up its neutral armature A_1 . The opening of back contact $39-40$ and the closing of front contact $39-38$ of magnet M_1 due to the picking up of armature A_1 interposes windings 14 and 15 of magnet M_2 and winding 49 of magnet M_1 in the circuit connection to the supply circuit. Current now flows in windings 14 , 15 and 49 in the same direction as in the previous case due to the transferring of the connection as effected by the contact $38-39$ of magnet M_1 and the action of asymmetric units 24 and 27 , and armature A_2 of magnet M_2 is held at the picked-up position. It is to be observed that the flux created by winding 49 now is additive with respect to the flux created by windings 12 and 13 so that the armature A_1 of magnet M_1 is retained at the picked-up position. Both armatures A_1 and A_2 being now picked up, the member 20 is operated to its third position. Operation of the apparatus of Fig. 5 in response to movement of the pole changer PC from the right-hand to the left-hand position is substantially the same as that described in connection with the apparatus of Fig. 3, and the description need not be repeated, except to point out that armature A_1 of magnet M_1 is released due to the reversal of the energization of magnet M_1 and then is subsequently held in its released position due to the differential action of winding 49 of magnet M_1 .

Although the apparatus is disclosed with the two tractive armatures interconnected for operation of a searchlight signal it is apparent they can be used to operate other signaling means and also can be used to operate contacts for control of an operating circuit with the interconnection omitted.

Although I have herein shown and described several forms of control apparatus for railway signaling means embodying my invention, it is understood that various changes and modifications may be made therein within the scope of the appended claims without departing from the spirit and scope of my invention.

Having thus described my invention, what I claim is:

1. In railway signal control apparatus the combination comprising, a supply circuit including a source of direct current and a pole changer, a first and a second electromagnet each having a neutral armature, means structurally a part of said first electromagnet to overcome the attractive force on its armature when that magnet is energized at normal polarity but not when the magnet is energized at reverse polarity, contact means structurally a part of said first electromagnet operated from a first to a second position only when that magnet is conditioned to pick up its neutral armature, said first electromagnet having a winding connected to said supply circuit to energize that magnet at a polarity corresponding to the polarity of the supply circuit current, said second electromagnet having a winding connect-

ed to said supply circuit through said contact means to energize that magnet at the same given polarity irrespective of the polarity of the supply circuit current, a linkage to interconnect said armatures, and a signal actuating member connected to said linkage to operate the member to one position when only the armature of said second electromagnet is attracted to its second position and to a different position when both armatures are attracted to their second positions.

2. In railway signal control apparatus the combination comprising, a supply circuit including a source of direct current and a pole changer to supply current of either normal or reverse polarity, a first and a second electromagnet each having a neutral armature biased to a released position and attracted to a picked-up position, means structurally a part of said first electromagnet to retain its armature at the released position when that magnet is energized at normal polarity but not when the magnet is energized at reverse polarity, contact means structurally a part of said first electromagnet operated from a first to a second position only when that magnet is energized at reverse polarity, said first electromagnet having its energizing winding connected to said supply circuit to receive current of normal or reverse polarity as predetermined by the position of said pole changer, said second electromagnet having its energizing winding connected to said supply circuit through said contact means to receive current that flows in that winding always in the same direction irrespective of the polarity of the supply circuit current, and a lever connected to both of said neutral armatures to connect said neutral armatures to a controlling member to operate that member to one position in response to supply circuit current of normal polarity and to a different position in response to supply circuit current of reverse polarity.

3. In railway signal control apparatus the combination comprising, a supply circuit including a source of direct current and a pole changer to supply current of either normal or reverse polarity, a first and a second electromagnet each having a neutral armature biased to a released position and attracted to a picked-up position, said first electromagnet provided with magnetic means which retains the neutral armature of that magnet at the released position when that magnet is energized at normal polarity and which means is ineffective when that magnet is energized at reverse polarity, said first electromagnet provided with contact means operable to a first or a second position according as that magnet is energized at normal or reverse polarity, said first electromagnet provided with an energizing winding connected to said supply circuit to receive current of normal or reverse polarity as predetermined by the position of said pole changer, said second electromagnet provided with an energizing winding connected to said supply circuit through circuit connections controlled by said contact means to receive current that flows always in the same direction irrespective of polarity of the supply circuit current, a signal actuating member operable to different positions, and linkage means to connect said actuating member to both of said neutral armatures to operate the member to one preselected position in response to a normal position of said pole changer and to a different preselected position in response to a reverse position of the pole changer.

4. In combination, a supply circuit including a circuit controller operable to three different

positions for the circuit to supply direct current of either normal or reverse polarity or to supply no current, a first and a second electromagnet each having a tractive type armature biased to a released position and attracted to a picked-up position, said first electromagnet having a polar armature which is disposed at its normal position to lock the tractive armature of that magnet at the released position, contact means connected to said polar armature to be operated to normal and reverse positions according to the normal and reverse positions of the polar armature, circuit means to connect energizing windings of said first and second electromagnets to said supply circuit and controlled in part by said contact means to deenergize said first electromagnet or to energize that magnet at normal or reverse polarity as predetermined by the position of said circuit controller and to deenergize said second electromagnet or energize that magnet at a given polarity as predetermined by the position of the circuit controller; a signal actuating member, and a linkage connected to both of said tractive type armatures and to said signal actuating member for that member to be operated to a first position when both tractive armatures are released, to a second position when the tractive armature of said first electromagnet is released and the tractive armature of said second electromagnet is picked up and to a third position when both such tractive armatures are picked up.

5. In combination, a supply circuit including a circuit controller operable to three different positions for the circuit to supply direct current either of normal or reverse polarity or to supply no current, a pair of electromagnets each having a tractive type armature biased to a released position and attracted to a picked-up position, one of said electromagnets equipped with a polar armature which is disposed at its normal position to lock the tractive armature of said one electromagnet at the released position, a contact member connected to said polar armature to engage a normal and a reverse polar contact in response to the normal and reverse positions of the polar armature, said normal and reverse polar contacts connected to the two terminals of a winding of the other one of the electromagnets, two asymmetric units in series connected to said terminals of said winding of said other magnet, a first winding of said one electromagnet having one terminal connected to one side of said supply circuit and its other terminal connected to a mid terminal of said asymmetric units, a second winding of said one electromagnet having one terminal connected to the other side of said supply circuit and its other terminal connected to said contact member to reversibly energize said one magnet and to energize said other magnet always at the same polarity, a signal actuating member, and a linkage connected to both of said tractive type armatures and to said signal actuating member for that member to be actuated to three different positions according as said supply circuit supplies current of normal or reverse polarity or is conditioned to supply no current.

6. In combination, a supply circuit including a circuit controller operable to a normal or a reverse or an open position for the circuit to supply direct current of either normal or reverse polarity or to supply no current, a first and a second electromagnet each having a tractive type armature biased to a released position and attracted to a picked-up position, said first electromagnet having a polar armature which is disposed at its nor-

mal position to lock the tractive armature of that magnet at the released position, pole changing contact members connected to said polar armature and operated to normal and reverse positions according to the normal and reverse positions of the polar armature, said first electromagnet having an energizing winding connected to said supply circuit to deenergize that magnet or energize the magnet at either normal or reverse polarity in response to the open or normal or reverse position of said circuit controller, said second electromagnet having an energizing winding connected to said supply circuit through said pole changing contact members to deenergize that in response to the open position of said circuit controller magnet or energize the magnet at a given polarity in response to either the normal or reverse position of said circuit controller, and said tractive type armatures interconnected by a lever to which lever a signal actuating member is connected to successively operate such actuating member to three different positions according as the supply circuit supplies no current or supplies current of normal polarity or of reverse polarity.

7. In combination, a supply circuit including a circuit controller operable to a normal or a reverse or an open position for the circuit to supply direct current of either normal or reverse polarity or to supply no current, a first and a second electromagnet each having a tractive type armature biased to a released position and attracted to a picked-up position, said first electromagnet having a polar armature which is disposed at its normal position to lock the tractive armature of that magnet at the released position, pole changing contact members connected to said polar armature and operated to normal and reverse positions according to the normal and reverse positions of the polar armature, said first electromagnet having an energizing winding connected to said supply circuit to deenergize that magnet or energize the magnet at either normal or reverse polarity in response to the open or normal or reverse position of said circuit controller, said second electromagnet provided with slow release characteristics and having a first and a second energizing winding connected together through an asymmetric unit and disposed to add the effects, said windings of the second electromagnet having their outside terminals connected to said supply circuit through said pole changing contact members to energize the second electromagnet at the same polarity irrespective of the polarity of the supply circuit current, said asymmetric unit to block a reversal of the current through said second electromagnet windings at pole changing conditions of said supply circuit, and said tractive type armatures interconnected by a lever to which lever a signal actuating member is connected to selectively operate such actuating member to any one of three different positions according as the supply circuit supplies no current or supplies current of either normal or reverse polarity and momentarily movement of the actuating member during a change in the current of the supply circuit is avoided.

8. In combination, an electromagnet provided with a tractive type armature biased to a released position and attracted to a picked-up position and with a polar armature operable to a normal and a reverse position, said polar armature disposed at a preselected one of its positions to mechanically lock the tractive armature at the released position to permit the tractive armature

to be picked up only when the electromagnet is energized at a predetermined polarity, and signaling means governed by said tractive armature.

9. In railway signal control apparatus the combination comprising, a supply circuit including a source of direct current and a pole changer to supply current of either normal or reverse polarity, a first and a second electromagnet each having a neutral armature biased to a released position and attracted to a picked-up position, a permanent magnet made a part of said first electromagnet and disposed to hold the neutral armature of that electromagnet at the released position when that magnet is energized at normal polarity but not when the magnet is energized at reverse polarity, pole changing contact members attached to the neutral armature of said first electromagnet, said first electromagnet having a winding connected to said supply circuit to energize that magnet at normal or reverse polarity according to the polarity of the supply circuit current, said second electromagnet having a winding connected to said supply circuit through said pole changing contact members to energize that magnet at the same polarity irrespective of the polarity of the supply circuit current, and said neutral armatures interconnected through a linkage to a signal actuating member to selectively operate the actuating member to either one of two different positions according to the polarity of the supply circuit current.

10. In combination, a supply circuit including a circuit controller operable to three different positions for the circuit to supply direct current of either normal or reverse polarity or to supply no current, a first and a second electromagnet each having a tractive type armature biased to a released position and attracted to a picked-up position when the respective magnet is energized, a permanent magnet made a part of said first electromagnet and disposed to retain the tractive armature of that electromagnet at the released position when that magnet is energized at normal polarity but not when energized at reverse polarity, pole changing contact members attached to the tractive armature of said first electromagnet, said first electromagnet having a winding connected to said supply circuit to energize that magnet at either normal or reverse polarity or to deenergize the magnet according as said circuit controller is set at its open or normal or reverse position, said second electromagnet having a winding connected to said supply circuit through said pole changing contact members and an asymmetric unit to energize that magnet always at the same predetermined polarity or to deenergize that magnet according as said circuit controller is set at its normal or reverse position or is set at its open position, said asymmetric unit to avoid a momentary reversal of the energization of said second electromagnet subsequent to a change in the position of said circuit controller, and said tractive armatures interconnected to a signal actuating member to operate such actuating member to any one of three different positions according to the positions of said circuit controller.

11. In railway signal control apparatus the combination comprising, a supply circuit including a source of direct current and a controller to supply current of either normal or reverse polarity or to supply no current according to a normal or a reverse or an open position of the controller, a first and a second electromagnet each having a neutral armature biased to a released

position and attracted to a picked-up position, a permanent magnet made a part of said first electromagnet and disposed to hold the neutral armature of that electromagnet at the released position when that electromagnet is energized at normal polarity but not when the electromagnet is energized at reverse polarity, a contact member attached to the neutral armature of said first electromagnet to engage front and back contacts; circuit means including a pair of asymmetric units in series and said contact member to connect an operating winding of each of said electromagnets in series to said supply circuit to deenergize both said electromagnets when no current is supplied to said circuits, to energize 15 said first electromagnet at normal or reverse polarity according to the polarity of the current of said supply circuit and to energize said second electromagnet at the same polarity irrespective of the polarity of the current of the supply 20 circuit; and said neutral armatures connected to a signal actuating member through a common linkage to operate said actuating member to a first, a second or a third position according as the supply circuit supplies no current, supplies current of normal polarity or current of reverse 25 polarity.

12. In railway signal control apparatus the combination comprising, a supply circuit including a source of direct current and a pole changer to supply current of either normal or reverse polarity, a first and a second electromagnet each having an armature biased to a first position and attracted toward a second position when the respective magnet is energized at either polarity, a contact member attached to the armature of said first electromagnet to engage a front or a back contact, said first electromagnet provided with a differential winding effective when energized in opposition to the energizing winding of that magnet to annul the flux created by such energizing winding, circuit means including an asymmetric unit and said contact member to serially con-

nect the energizing windings of said first and second electromagnets and said differential winding to said supply circuit to pick up only the armature of the second electromagnet when the current of the supply circuit is of normal polarity and to pick up both said armatures when the current is of reverse polarity, and said armatures connected through a linkage to a signal actuating member to operate such actuating member to different positions according to the polarity of the current of the supply circuit.

13. In railway signal control apparatus the combination comprising, a supply circuit including a source of direct current and a pole changer to supply current of either normal or reverse polarity, a first and a second electromagnet each having a neutral armature, a contact member attached to the armature of said first electromagnet to engage a front or a back contact, said first electromagnet provided with a differential winding effective when energized in opposition to the energizing winding of that magnet to retain the armature of that magnet at its released position, a first circuit means including said contact member and back contact and a first asymmetric unit to connect in series the energizing winding of each of said electromagnets and said differential winding to said supply circuit with the differential winding in opposition to the energizing winding of said first electromagnet to pick up the armature of said second electromagnet only when the current of the supply circuit is of normal polarity, and a second circuit means including said contact member and front contact and a second asymmetric unit to connect in series said energizing windings and said differential winding to said supply circuit with the differential winding aiding the energizing winding of the first magnet to pick up both said armatures when the current of the supply circuit is of reverse polarity.

WESLEY B. WELLS.

CERTIFICATE OF CORRECTION.

Patent No. 2,361,516.

October 31, 1944.

WESLEY B. WELLS.

It is hereby certified that error appears in the printed specification of the above numbered patent requiring correction as follows: Page 7, first column, line 15, claim 6, after "that" insert --magnet--; line 16, same claim, after "controller" strike out --magnet--; page 8, first column, line 15, claim 11, for "circuits" read --circuit--; and that the said Letters Patent should be read with this correction therein that the same may conform to the record of the case in the Patent Office.

Signed and sealed this 23rd day of January, A. D. 1945.
